ANTIAIRCRAFT FIRE CONTROL PREDICTOR

Earl W. Chafee, New York, N. Y., and Bruno A. Wittkuhns, Summit, N. J., assignors to Sperry Gyroscope Company, Inc., Brooklyn, N. Y., a corporation of New York

Application October 5, 1937, Serial No. 167,358

14 Claims. (Cl. 235—61.5)

This invention relates to fire control directors, particularly of the anti-aircraft type, wherein the relative speed of the target is great. This application discloses in greater detail how the rate determining and introducing means disclosed in our prior application Serial No. 75,526, filed April 21, 1936, now Patent No. 2,206,875, dated July 9, 1940, for Fire control devices, is applied in a complete modern director of the type disclosed in the prior patent to Earl W. Chafee, Hugh Murtagh and Shierfield G. Myers, No. 2,065,303, dated December 22, 1936, for Apparatus for control of gun fire. The present application is therefore a continuation in part and further amplification of our aforesaid prior application.

A further object of the invention is to improve this system of fire control by adapting it for gliding targets by introducing a means for determining rate of change of altitude as well as the resolved x and y rates in a horizontal plane.

Referring to the drawings, illustrating the invention in diagrammatic form,

Figs. 1A and 1B are the two halves of a diagram showing the principal component parts of our invention, Fig. 1A being a substantial reproduction of Fig. 1A of Patent 2,065,303 and Fig. 1B showing the new rate means in place of the tachometers of the patent, plus the elevation rate device.

Fig. 2 is a diagrammatic view showing on a larger scale the mechanism for determining the target displacement during the time of flight of the shell, this figure being substantially the same as Fig. 5 of our aforesaid prior application.

Fig. 3 is a plan view of one of the resolving mechanisms, being taken from the aforesaid prior patent.

Fig. 4 is a modification of the arrangement of Fig. 2 and is substantially the same as Fig. 3 of our prior application above referred to.

As explained in said prior patent, the sights ET and AT are maintained on the target by the elevation handwheel EH and the azimuth handwheel AH, the latter rotating the entire director and sights around fixed gear 1. Altitude is also continuously fed into the machine from a height finder (not shown) through repeater motor 2. The elevation angle E_0 appears at E_0 and E_0' on the coarse and fine indicators 23 and 23' and the azimuth angle A_0 on coarse and fine indicators A_0 and A_0' , while the altitude H_0 appears at dial H_0 . Present horizontal range R_0 is computed by the machine from the setting of three dimensional cam 10 which solves the equation

$$R_0 = \frac{H_0}{\tan E_0}$$

Said cam is positioned laterally by means of shaft 12 on which its support 11 is threaded, said shaft being turned from present range setting handle

13. The cam is also rotated in accordance with the altitude H_0 from handwheel H which is turned until index 16 matches pointer 216. The lift of cam pin 19 rotates, through rack and pinion 20' and shafts 21' and 22, the pointers 223 and 223' on the elevation angle indicators E_0 and E_0' . The cam is so laid out that with the correct height H_0 and elevation angle E_0 set into the machine, the rotation of the present range handle 13 to match the pointers and indices of indicators E_0 , E_0' will be a measure of the horizontal range R_0 . The elevation angle E_0 is set on the indices 23 and 23' of indicators E_0 and E_0' from the handwheel EH, (which maintains the sight on the target in elevation) through shafts 201 and 202, worms 203 and 203' and step-up gearing 204. Each pointer and index 223 and 223' reads on the same fixed dial or scale 224 and, similarly, pointer and index 223' and 223' read on the dial 223'. As the elevation angle changes, the operator of handle 13 preferably shifts to the range rate handle 24. This handwheel turns a dial 25 and positions the shiftable member of a change speed device. As shown it positions a ball or balls 26 operating between a disc 27 turned from a constant speed motor 28 and a cylinder 29. Said cylinder operates the same shaft 30 as the handwheel 13 through a differential 31, and thus when handle 24 is set so that follow-the-pointer indicators E_0 and E_0' stay matched, the correct rate of change of range has been set up. Similarly, as the altitude changes, the operator shifts to handle H' which positions the shiftable member 28' of similar variable speed device 29' which turns the same shaft 14' through differential 15' to position cam 10 rotationally by turning shaft 14. Shaft 30 not only positions the cam 10 axially, as explained, but also operates the cross shaft 31' and the shafts 32 and 33 driving present range into the present position resolving mechanism 34, and also leading to the future mechanism 35. Similarly the azimuth angles A_0 are set in from the handwheel AH through shafts 36, 37 and 38, the latter being connected to the present mechanism 34 through shaft 39 and to the future mechanism through shaft 40. Said mechanisms are preferably superimposed and may be of identical construction (see also Fig. 3). Each mechanism may comprise a large gear 41 having a spiral groove 42 in the upper face thereof. Said gear, in the case of the present mechanism, is turned from the range shafts 30, 32 through a pinion 45. Superimposed thereon is a second concentrically mounted gear or plate 43 having a radial slot 44 therein which is rotated by a pinion 48 on the azimuth shaft 39. In said slot is slidably mounted a block 47 having pins and rollers thereon, the lower roller engaging the spiral

groove 42 and the upper pin 48 passing through slots 49 and 50 in the superimposed slides 51 and 52. It will readily be seen that the angular position of block 47 about the center of rotation O of said gear is the azimuth angle A_0 and the distance along the radius is the range R_0 . Said plates or slides are constrained by slideways 53 and 54 to move at right angles to one another and it will readily be seen that the rectilinear displacements thereof represent the component displacements of the ground course of the target when the range gear or disc 41 is set in accordance with the present horizontal range and the azimuth gear or disc 43 is set in accordance with A_0 . The differential 50' is for the purpose of preventing the range from being changed when only A_0 is being changed by causing the two gears to move together under such conditions.

As above stated, the future resolving mechanism may be quite similar in construction but in this case the range gear 41' is rotated by a shaft 33 which is driven not only from the present range shaft 31' but also from a "range difference" motor 98 or change of range motor through a differential 97. Similarly the azimuth gear 43' is driven from shaft 40 which is rotated not only by the shaft 38 but also from the "azimuth difference" motor 98 through shafts 99 and 100 and differential 101. The vertically movable slide 52' in this instance is shown as turning a shaft 110 through rack and pinion 111. On said shaft is mounted one portion 86' of follow-up contacts 86-86'. Plate or slide 51', on the other hand, is shown as turning through similar rack and pinion 111' one portion 83' of follow-up contacts 83-83', the complementary contacts in each case being driven by one or the other of the range or azimuth difference motors as was more fully explained in the aforesaid patent.

Returning to the present resolving mechanism, the rates of movement of the two slides 51 and 52 are, of course, proportional to the rate of displacement of the target in the two component directions. To determine such rates, we actuate from the up and down movements of slide 52, a shaft 56 through a rack and pinion connection 57; and through a similar connection 57' we operate the shaft 58 from the right and left movement of slide 51.

Shafts 56 and 58 both are connected (the latter by way of shaft 63) to rate and displacement determining devices which constitute a marked improvement over the rate and displacement devices of said prior Patent 2,065,303, and which are substantially the same as shown in Fig. 5 of our aforesaid application, now Patent No. 2,206,875, reproduced herein as Fig. 2. The essential element of the device is a variable speed gear comprising a power driven disc, a radially adjustable ball carriage thereon, a cylinder driven thereby and a three arm differential, one arm of which is driven by displacement of the target along one axis, another arm of which is driven by the cylinder of the variable speed drive and the third arm of which is operatively connected to adjust the radial position of the ball carriage thereof. With such an arrangement, if the disc of the variable speed gear were to be driven at a constant speed (as is disc 278 of Fig. 4 referred to hereinafter), the position of the ball carriage would be automatically adjusted, radially, on the disc so that when a state of equilibrium was reached, the distance of the ball carriage from the center of rotation of the disc would be a measure of the target's rate of displacement R along the chosen

axis. In the arrangement of Fig. 2 an additional factor is introduced by varying the speed of rotation of disc 76 in accordance with the reciprocal of time of flight of the shell

$$\frac{1}{T}$$

the two factors, R and

$$\frac{1}{T}$$

being thus divided, as will be explained more in detail hereinafter, to give RT , the predicted displacement of the target during the flight of the shell, this product being measured by the displacement of the ball carriage from the center of the disc. This interconnected variable speed gear and differential gear may be termed a self-adjusting variable speed gear. Other variable speed drives, without the self-adjusting feature derived from the connection to the differential, are also employed where it is desired merely to convert a displacement into a rate of rotation, as will be described in connection with the introduction of

$$\frac{1}{T}$$

and the wind correction.

As shown in Fig. 2, the x component of target displacement is supplied to the x prediction computing device by way of shaft 63 which drives one arm of wind correction differential 59, the middle or second arm of which is driven from roller 10 of wind correction variable speed gear 71 and the third arm of which drives one arm of a second differential 72 by way of shaft 189. The opposite or second arm of said differential 72 is driven by roller 73 of the prediction variable speed gear 74, while the third arm radially positions the ball or balls 75 of gear 74 on rotated disc 76. Said disc, as has been noted, is rotated at a variable speed from the roller 71 of a third variable speed gear 78, the radially adjustable balls of which, driven from disc 80, are positioned by a cam pin 79, riding on cam T, whose lift is inversely proportional to the time of flight of the shell, i. e., proportional to

$$\frac{1}{T}$$

The contour of cam T is computed from firing tables giving time of flight of a shell as a function of future or predicted horizontal range R_p and predicted altitude H_p , and the cam, which is three-dimensional, is positioned rotationally and axially in proportion to R_p and H_p , respectively, by means hereinafter described.

Disc 80 of gear 78 is constantly driven, as from constant speed motor 181, which may also serve as the source of power for the constant speed discs of the x wind correction mechanism 71 (disc 182) and the y wind correction mechanism 183 (disc 184, Fig. 1B). Disc 76 is therefore driven from cylinder 77 at a rate proportional to

$$\frac{1}{T}$$

and since, when the self-adjusting variable speed gear comprising gear 74 and differential 72 reaches a state of equilibrium, the rate of rotation of cylinder 77 must be equal to or proportional to the rate of rotation of shaft 189, ball carriage 75 will be automatically positioned to impart

such speed to cylinder 73. In this self-adjusting arrangement differential 72 serves as an equalizer of the speeds of shaft 189 and cylinder 73, since if these speeds, as fed into two arms of the differential, are unequal, the third arm of the differential is caused to rotate shaft 185 and thereby through pinion 187 and rack 186 change the radial position of ball carriage 75 until equilibrium is established. The radial displacement d of ball carriage 75 when this equalizing action is completed, will, upon analysis, be found to be greater the less the speed of disc

$$76 \left(\frac{1}{T} \right)$$

and the greater the speed of shaft 183(R). In mathematical form,

$$d = \frac{R}{\frac{1}{T}} = RT$$

This product, which is measured by the displacement of carriage 75, is transmitted as the angular displacement of shaft 185, geared to rack bar 186, connected to ball carriage 75 through pinion 81, and is added to the displacement of slide 51, representing present position of the target, by way of shaft 81' and differential 182, to position the future x slide 51' in accordance with the future or predicted position of the target through a power multiplying device hereinafter described.

The wind correction obtained from device 71 as the rate of rotation of cylinder 70 is added to the rate of target displacement as an accelerating or retarding factor by the differential 59 so that it is this corrected rate that is fed into differential 72 by shaft 182. The ball carriage 180 of the wind device 71 is radially displaceable by handwheel 200 in accordance with the x component of wind velocity effective in deflecting the shell. Such displacement causes cylinder 70 to be driven at a velocity proportional to the correction to target velocity necessary to compensate for the wind-induced deflection or retardation of the shell. In this manner the rate of change of target position, as represented by the rate of rotation of shaft 63, is corrected for the effect of wind velocity before being multiplied by T in the operation of computing predicted target displacement during the flight of the shell.

The prediction mechanism for the y axis may be identical with that above described. Shafts 56 and 61' are connected to the y wind correction device 183 (Fig. 1B), by way of which a wind correction is set by knob 201, and also to device 180 for obtaining the prediction correction along the y axis. The disc of device 180 may be rotated from the same

$$\frac{1}{T}$$

device 78 that rotates disc 76 of device 74. The predicted change of target position is indicated by the radial position of ball carriage 131 of device 180 which is transmitted by shaft 84 to differential 182 where it is added to the present position to give future position of the target along the y axis.

As stated above, according to the present invention we prefer also to introduce a future height or altitude predicting means, so that the director is equally well adapted to predict the positions of gliding targets. We again employ

the output of device 78, having a rate of rotation proportional to

$$\frac{1}{T}$$

5 to rotate disc 133 of variable speed device 134 and we feed into equalizing differential 135 of the altitude prediction self-adjusting variable speed gear (1) the height of the target as determined by the settings of handwheels H, H' , which set in a displacement and a rate of change of displacement, respectively, and as measured by the angular positions of shafts 14', 51, 38, 39 and 39', and (2) the rotation of cylinder 186, so that in the 10 radial position which ball carriage 137 takes up, its distance from the center of the driving disc is proportional to the quotient of rate of altitude 15 change and

$$\frac{1}{T}$$

20 or to the product of altitude rate and T . This multiplication of the rate of change of altitude and time of flight by means of an inter-connected variable speed drive and differential occurs in the 25 manner previously described in connection with predicted target displacements in a horizontal plane. The position of carriage 137 therefore indicates total change of altitude during the time, T , of the flight of the shell, which is algebraically 30 added to present altitude through follow-up device 140 (which may be controlled by contacts functioning in a manner similar to contacts 83, 83' and 86, 86'), and differential 141 to give shaft 142 an angular position representing future altitude

35 35 We employ this future altitude to position in one dimension, say axially, the time of flight cam T and preferably also the quadrant elevation cam QE and the fuse setter cam F . Said cams are 40 rotationally positioned in accordance with future horizontal range R_x from shafts 93 and 92.

The apparatus shown diagrammatically in Fig. 4 is a modification of the arrangement of Fig. 2 for predicting change of target position during the 45 flight of the shell and may be employed for prediction along any or all of the three axes, certain elements being included to adapt the apparatus to prediction in the horizontal plane which may be dispensed with for altitude or height prediction, as will be pointed out. The displacement of 50 slide 251 (corresponding to slide 51 of Fig. 2) represents target displacement along a chosen axis and is transmitted by gearing to shaft 263 driving one arm of differential 272, a second arm of which 55 is driven by roller 273 of variable speed device 274. In this device, the disc 276 is driven at a constant speed from motor 281 and, in accordance with the 60 previously described operation of such self-adjusting variable speed devices, when equilibrium is reached, ball carriage 275 is displaced from the center of disc 276 an amount which causes roller 273 to be driven at the same speed as shaft 263. Since, with disc 276 driven at a constant speed, the roller speed varies directly and solely 65 with the displacement of the ball carriage, this displacement represents rate of change of target position along the chosen axis.

The references to slides 251 and 251' in the 70 above description of the prediction mechanism of Fig. 4 relate more particularly to the mechanism for calculating prediction in the horizontal plane where the displacements of these slides represent components of present and future target position changes. It will readily be appreciated that, for 75 altitude prediction, where according to Fig. 1B

present and future target altitude are represented by angular positions only, shafts 263 and 281' will not be geared to the aforementioned slides but that present altitude, as represented by the angular position of shaft 38, for example, may be supplied to the mechanism of Fig. 4 by any suitable mechanical connection to position shaft 263 correspondingly and that altitude prediction as computed by said mechanism and as represented by the position of cam pin 279 or the shaft rotated by said pin, may be reproduced as a corresponding angular position of shaft 140' (Fig. 1B).

It will be apparent that the principal difference between the prediction means shown in Figs. 2 and 4, respectively, is that in the arrangement of Fig. 2, time of flight is introduced into the prediction self-adjusting variable speed device by way of disc 76, so that the displacement of the ball carriage of said device represents the product of the two factors, rate of change of target displacement and time, while in the arrangement of Fig. 4 the disc of the variable speed device is driven at a constant speed and the displacement of the ball carriage represents target rate only, which is multiplied by time by independent cam means. As noted, either of the two arrangements may be used in obtaining change of target position along any of the three axes.

Returning to the future resolving mechanism, each of the two slides 52' and 51' of the future mechanism positions a contact, 86' or 83', cooperating with one or the other of contacts 86 and 83, as hereinbefore explained. Said contacts operate the range difference and azimuth difference motors 96 and 98 preferably through the connections more fully explained in Patent No. 2,065,303. Thereby the future resolving mechanism receives the predicted coordinates of the target's position from which the future range R_p and future azimuth angle A_p may be determined by the angular position of the two gears 41' and 43'. The former is represented by the rotation of the shaft 38 and the latter by the rotation of the shafts 40, 40', which is indicated as future azimuth by the coarse and fine dials A_p and A_p' . Into said dials corrections may be introduced from the handwheel 104 which rotates the field of the A_p transmitter 105 transmitting the future azimuth angle to the gun through the cable 106.

A consideration of the problem being solved by the future resolving mechanism will show that it converts the two rectangular coordinates of the future position of the target into polar coordinates, range R_p and azimuth angle A_p , or, in other words, that the mechanism solves for two unknowns simultaneously and that the entire system continuously integrates for these unknowns, the machine operating by what may be termed the flow method by which the correct future position is obtained very quickly although every change in each variable alters the setting for the other variables. Therefore, both motors 96 and 98 operate simultaneously and each influences the position of the other.

Since the gunners must know the quadrant elevation at which the guns must be pointed, which is the sum of the future elevation angle and the "super" elevation, and since both future elevation and superelevation are functions of future horizontal range R_p and altitude H_p , we prefer to compute the sum of the two on the same cam QE to give quadrant elevation. Future range R_p represented by the rotation of the shaft 38 may, therefore, be used to rotationally position the cam shaft 92 of the cams QE, F and T.

With the quadrant elevation cam properly laid out, therefore, the lift of the pin 112 thereon will represent the quadrant elevation, i. e., future elevation plus superelevation, this lift being transmitted through rack and pinion 113 to rotate the quadrant elevation transmitter 114 to send out quadrant elevation to the guns. If desired, coarse and fine quadrant elevation dials 115 and 115' may be provided at the instrument. 10 Similarly, if the fuse cam F is properly laid out, the lift of the pin 118 will represent the fuse setter's data and this may be transmitted through the transmitter 119 to the gun. Similarly, fuse corrections may be introduced through the handle 120.

As many changes could be made in the above construction and many apparently widely different embodiments of this invention could be made without departing from the scope thereof, it is 20 intended that all matter contained in the above description or shown in the accompanying drawings shall be interpreted as illustrative and not in a limiting sense.

Having described our invention, what we claim and desire to secure by Letters Patent is:

25 1. In a fire control predictor, means actuated in accordance with the present position of the target, a future position means, and means for advancing said second means ahead of said first means in accordance with the advance in position of the target during the time of flight of the shell, including power actuated mechanical means for converting the movement of said first means into a positional displacement proportional to rate, means actuated directly from said displacement for multiplying said displacement by function of time, and means actuated directly thereby for positioning said second means.

30 2. In a fire control predictor, means actuated in accordance with the present position of the target, a future position means, and means for advancing said second means ahead of said first means in accordance with the advance in position of the target during the time of flight of the shell, including a driving member, a frictional driven intermediate member, the speed of which relative to that of the driving member varies with its position thereon, a third member driven by said intermediate member, said intermediate member being differentially positioned by said present position means and said third member, means positioned by the position of said intermediate member for actuating the future position means, and means for rotating said driving member at a speed inversely proportional to the time of flight of the shell.

35 3. A fire control predictor as claimed in claim 2, in which a correction for wind deflection is secured by a variable speed device having a member positionable to effect change of output speed thereof, said change speed member being positioned in accordance with the wind velocity effect and the resultant output motion of said device added to the motion of the present position means in differentially positioning said intermediate member.

40 4. In a fire control director of the rectilinear plan coordinate type having means for determining the time of flight of the shell and quadrant elevation determining means, means for feeding in constantly changing altitude as determined by a height finder, a constant speed motor, a variable speed device and differential gear interconnected for automatically determining 45 from said altitude data rate of change of

altitude, said variable speed device being driven by said constant speed motor, means for combining rate of change of altitude with time of flight to obtain altitude change during flight of the shell, and means for feeding the sum of altitude and change of altitude to said quadrant elevation determining means for positioning the same according to future altitude.

5. In a fire control director, means for continuously resolving the target's position into rectilinear components, self-adjusting variable speed devices equal in number to said components, each including differential means interconnecting movable members thereof, means for actuating each of said devices jointly in proportion to change of one of said components and time of flight of the shell for positioning a member in accordance with the product of the rate of change of said actuating component and time of flight, said product representing change of said target position component during flight of the shell.

6. In a fire control director having individual means displaceable to represent component changes of target position along each of three coordinate axes during flight of the shell, means in part controlling the displacement of said individual means in accordance with the rates of resolved target displacement along the respective axes, a time of flight three-dimensional cam, a cam pin actuated thereby, means for positioning said cam in one dimension in accordance with future altitude and in the other dimension in accordance with future range, the lift of the pin thereon being inversely proportional to the time of flight, means for converting said lift into a proportional rate, and means for driving another member of said individual means in accordance with said rate.

7. In a fire control director, means for computing quadrant elevation including a three dimensional cam and a cam follower, said cam and follower being mounted for relative rotation and axial movement to raise or lower the follower, future range means for imparting one of said movements and future altitude means for imparting said other movement including present altitude means, time of flight means, an interconnected variable speed device and differential gear adapted to receive present altitude and time of flight and automatically compute therefrom change of altitude during the flight of the shell, and means for combining present altitude and change of altitude to obtain future altitude, said cam being laid out so that the lift at each point represents quadrant elevation for the corresponding future range and altitude.

8. In a fire control director, means for continuously resolving the target's position into rectilinear components fixed in azimuth; individual self adjusting variable speed gears actuated from each component movement, the adjustable elements of which position themselves from a reference point proportionally to a function of the rate of movement along each component, and means for further causing the positions of said elements to be proportional to a function of time of flight of the shell, means for combining the displacements of said adjustable elements as representing component changes of target position during flight of the shell with said components of the target's position to give future coordinate positions, and means for reconverting said last named positions into future target elevation and bearing.

9. In a fire control predictor, means actuated in accordance with the present position of the target, a future position means, and means for advancing said second means ahead of said first means in accordance with the advance in position of the target during the time of flight of the shell, including a differential gear and a self-adjusting variable speed gear into which said first named means feeds, said variable speed gear having a driving element and a self-adjusting driven element, said self-adjusting feature being obtained by interconnection to said differential gear, and means for driving said driving element in inverse proportion to the time of flight of the shell, whereby the radial position of said driven element is proportional to the change of target position during the shell's flight.

10. A fire control predictor as claimed in claim 9, having a second variable speed device, means for setting a wind correction into the same, and means for algebraically adding the output thereof into said present position means, whereby the future position is also corrected for wind deflection.

11. A fire control director as claimed in claim 5 in which said variable speed devices each include a member rotated in accordance with time of flight and said positioned member is a ball adjustably positionable away from the axis of rotation of said rotated member to be driven at a variable speed thereby.

12. In a fire control director of the rectilinear plan coordinate type having means for determining the time of flight of the shell and quadrant elevation determining means, means for feeding in constantly changing target altitude as determined by a height finder, a self-adjusting variable speed device including differential means interconnecting movable members thereof, said device having a member automatically positioned in accordance with a function of two variable quantities actuating said device, means for supplying a function of time of flight to said device as one of said quantities, means for supplying rate of change of altitude as the other of said quantities, change of position of said member then being a measure of change of altitude during the flight of the shell, and means for positioning said quadrant elevation means in accordance with the sum of present altitude and said change of altitude, said sum representing future altitude.

13. In a fire control director future altitude means, comprising means for continuously setting present target altitude as determined by a height finder, time of flight means, a variable speed device including a driving member actuated by said time of flight means in accordance with a function of time of flight, a positionable intermediate member driven thereby and a third member driven by said intermediate member at a rate governed by the position of said intermediate member, means actuated jointly by said present altitude means and said third member for positioning said intermediate member to cause said third member to be driven at a rate proportional to rate of change of present target altitude, said intermediate member being thereby displaced from a reference position in proportion to the product of said rate and time of flight, and means for combining the displacement of said intermediate member, as representative of change of target altitude during flight of the shell, with present target altitude to obtain future target altitude.

14. In a fire control director, means for predicting change of altitude during flight of the shell comprising means for displacing a first independent member in proportion to change of altitude, means for displacing a second independent member at a rate proportional to the reciprocal of time of flight, and means for causing said two displacements jointly to displace a third

5 member in proportion to the quotient of rate of change of altitude and the reciprocal of time of flight, displacement of said last member thereby representing predicted change of altitude during flight of the shell.

EARL W. CHAFEE.
BRUNO A. WITTKUHNS.
